UNITED STATES PATENT OFFICE.

JOHN MANN, OF BUTTE CITY, CALIFORNIA.

DESIGN FOR A POST-HOLE AUGER.

SPECIFICATION forming part of Design No. 32,852, dated June 19, 1900.

Application filed May 24, 1900. Serial No. 17,887. Term of patent 14 years.

To all whom it may concern:

Be it known that I, JOHN MANN, a citizen of the United States, residing at Butte City, in the county of Glenn and State of California, have invented and produced a certain new and original Design for Post-Hole Augers; and I do declare the following to be a full, clear, and exact description of the invention, such as will enable others skilled in the art to 10 which it appertains to make and use the same.

The invention relates to a new and original design for a post-hole auger; and it consists of a design of the shape and configuration shown in the accompanying drawings, in which—
15 Figure 1 is a perspective view of the design. Fig. 2 is a side elevation taken from a different position. Fig. 3 is a back view, and Fig. 4 is a horizontal sectional view looking toward the point.

The leading features of the design comprise the blade 1, semicircular in cross-section and having beveled edges 2, the lip 3, having beveled edges and curved inwardly and forming a continuation of the curve of the blade, said blade and said lip at their 25 lower ends tapering inwardly, and an upwardly-projecting rod 4 and a cross handle-rod 5.

What I claim is—

The design for a post-hole auger as herein 30 shown and described.

In testimony whereof I have hereunto set my hand in presence of two subscribing witnesses.

JOHN MANN.
